CLAIM

The ornamental design for a metering bottle, as shown.

DESCRIPTION

FIG. 1 is an elevational view of a metering bottle showing my new design, the opposite side being substantially the same in appearance;

FIG. 2 is a view looking from the right of FIG. 1, the opposite side being substantially the same in appearance;

FIG. 3 is a top plan view;

FIG. 4 is a bottom plan view; and

FIG. 5 is a view partially in section taken substantially on the line 5—5 of FIG. 3.

FIG. 1

FIG. 2

FIG. 5

FIG. 3

FIG. 4
